RUBBER BABY PANTS

Paul E. Ambrose, Dover, Del., assignor to International Latex Corporation, Dover, Del., a corporation of Delaware

Application January 11, 1955, Serial No. 33,928

Term of patent 14 years

(Cl. D3—17)

Fig. 1

Figure 1 is a view of the front of a pair of rubber baby pants embodying my new design, the back of the pants having an identical design;

The characteristic feature of my design resides in the combination on the baby pants disclosed of the sinuous, smooth bands bordering the waist and leg openings which give the effect of being raised above the surface of the baby pants as shown.

I claim:

The ornamental design for rubber baby pants, as shown and described.
